UNITED STATES PATENT OFFICE.

FRANKLIN W. KELLY, OF VERNONTVILLE, MICHIGAN.

SHUTTER-WORKER.

SPECIFICATION forming part of Letters Patent No. 391,898, dated October 30, 1888.

Application filed February 8, 1888. Serial No. 263,385. (No model.)

To all whom it may concern:

Be it known that I, FRANKLIN W. KELLY, of VERNONTVILLE, in the county of Eaton and State of Michigan, have invented a new and useful Improvement in Shutter-Workers, of which the following is a full, clear, and exact description.

This invention relates to an improvement in shutter-workers in which a gear-wheel is fixed concentrically to the eye of the shutter-hinge leaf, and is engaged for swinging the shutter by a pinion on a turning spindle passing through the window-casing, and provided on its inner end with an operating-handle and a clutch device for locking or releasing the spindle.

The object of my improvement is to prevent the outside gearing from becoming clogged or injured by rain, ice, or snow, to provide for a ready detachability of parts for inspection or repairs, and to render the clutch mechanism on the operating-handle safer to work and more durable.

The invention consists of certain novel combinations of parts and details of construction, hereinafter fully described, and distinctly pointed out in the claim.

Reference is to be had to the accompanying drawings, forming a part of this specification, in which similar letters of reference indicate corresponding parts in all the figures.

Figure 1 is an outside view of a window having shutters provided with workers embodying my improvement. Fig. 2 is an enlarged inverted sectional plan view of a part of the same, taken on the line *xx*, Fig. 1. Fig. 3 is a sectional elevation of a part of the same, taken on the line *yy*, Fig. 2. Fig. 4 is a longitudinal sectional elevation of the spindle-handle and clutch device, taken on the line *zz*, Fig. 2.

The upper and lower hinges, *A A'*, for each shutter *B* have their leaves *C C'* preferably curved laterally outward to bring the hinge-pins *D*, when said leaves are secured in the ordinary manner to the shutter *B* and the casing *E*, respectively medially in front of the casing.

The swinging shutter-leaf *C* of each lower hinge, *A*, is formed with a double eye, *F*, so as to embrace the single eye on the fixed casing-leaf *C'*, and on the top of the double eye *F* is formed

integrally and concentrically therewith an inverted crown-wheel, *G*, having downwardly-coned bevel-teeth *H*, a closed roof projecting outward beyond the teeth *H* and a circular flange, *I*, depending from the edge of the roof, so as to prevent snow or rain from reaching the gear-teeth. A spindle, *J*, having squared outer and inner ends, *J'* and *J''*, respectively, is passed through the window-casing *E* on each side in line with the hinge-pins *D*, and is mounted to turn in end bearings, *K K'*, fixed to the casing. A bevel-pinion, *L*, having a square socket, is introduced between the flange *I* and the bevel-teeth *H* on the inverted crown-wheel *G* in position to receive in its square socket the squared outer end, *J'*, of the turning spindle *J*, which end is fitted to the socket. The bevel-pinion *L* is thus held in place by the flange *I* on the one side and the crown-teeth *H* on the other, and can be easily removed on simply withdrawing the spindle.

A pin, *M*, is passed transversely through the spindle *J* just inside the casing *E*, and the inside spindle-bearing, *K'*, is formed with an annular recess, *K''*, in its inner abutting face, to permit the pin to turn freely with the spindle, while preventing the spindle from being drawn inward.

The outer end of the bearing *K'* is formed with a circular clutch-section, *N*, and the squared inner end, *J''*, of the spindle, which projects from the bearing *K'*, is inserted in a socket, *O*, considerably larger than the same, formed in a handle, *P*.

The outer end of the socket *O* has fixed thereto a contracted and square-holed collar, *O'*, to fit closely the squared end *J''*, but to play lengthwise thereon, and on the squared end *J''*, considerably within the collar *O'*, is fixed a collar, *Q*, between which and the collar *O'* a coiled spring, *R*, is interposed. The outer end of the collar *O'* has also fixed thereto or formed thereon clutch-teeth *N'*, which are adapted to be held normally engaged with a fixed clutch-section, *N*, by the pressure of the spring *R*, and thus lock the handle, turning spindle, and hence shutter, in place. The square end *J''* is formed also with a limited longitudinal slot, *S*, to receive a pin, *T*, fixed to the outer handle, *P*, and permit the same to be drawn outward just far enough to disengage the clutch-sections *N N'*.

The spindle can then be turned by the handle to swing the shutter to any desired position, and when the handle is released the whole mechanism will be automatically locked, as 5 before.

Having thus described my invention, what I claim as new, and desire to secure by Letters Patent, is—

In a shutter-worker, the operating-rod J, 10 having a reduced angular outer end, J², provided with a recess, S, the bearing K, through which the round part of rod J passes, provided with an annular recess, K², in its inner face, and having a clutch-section, N, on its outer

face, the pin M, passed through rod J and 15 working in the recess K², the handle P, having a socket, O, the collar O', secured to the knob and having an angular opening, through which the part J² of the rod J passes, and a clutch-section, N', on its outer face, the collar 20 Q and spring R on part J² within the socket, and the screw or pin T, passing through the wall of the socket into the recess S, substantially as set forth.

FRANKLIN W. KELLY.
